B. F. KELSO,
FLY SWATTER,
APPLICATION FILED JUNE 12, 1919.

1,334,246.

Patented Mar. 16, 1920.

UNITED STATES PATENT OFFICE.

BENJAMIN F. KELSO, OF HEMET, CALIFORNIA.

FLY-SWATTER.

1,334,246.

Specification of Letters Patent. Patented Mar. 16, 1920.

Application filed June 12, 1919. Serial No. 303,591.

To all whom it may concern:

Be it known that I, BENJAMIN F. KELSO, a citizen of the United States, residing at Hemet, in the county of Riverside and State 5 of California, have invented certain new and useful Improvements in Fly-Swatters; and I do declare the following to be a full, clear, and exact description of the invention, such as will enable others skilled in the art to 10 which it appertains to make and use the same.

On all types of fly swatters commonly employed there is a great strain exerted on the wire gauze at its point of connection with the handle and this usually causes breakage 15 of the gauze, resulting from continual bending thereof during the operation of the swatter. Furthermore, the forms of attaching means commonly used for connecting the gauze to the handle, are prone to 20 tear loose from the gauze. My invention has for its object to overcome these difficulties and at the same time to provide a swatter which will be simple and inexpensive.

With the foregoing in view, the invention resides in the novel construction hereinafter described and claimed, and shown in the accompanying drawing.

Figure 1 is a side elevation of one form of swatter constructed in accordance with my 30 invention.

Fig. 2 is an edge view.

Fig. 3 is an enlarged vertical section on the plane indicated by the line 3—3 of Fig. 1.

Fig. 4 is a view similar to Fig. 3, illustrating a different form of construction.

Fig. 5 is a perspective view of the gauze holder shown in Fig. 4.

In the drawing above briefly described, the numeral 1 designates a wire gauze body 40 whose rear corners are folded upon themselves at 2, the entire rear portion of the gauze being then folded forwardly upon itself as indicated at 3. The front end of the body 1 may be bound as indicated at 1^a if desired. A channel shaped sheet metal holder 4 straddles the folded rear end of the gauze body 1 and may be constructed either as shown in Figs. 1, 2 and 3, or as illustrated in Figs. 4 and 5. Under either 45 construction, the front diverging ends 5 of a twisted wire handle 6, pass through the holder and the rear end of the gauze body 1 to simultaneously retain said body in said holder and secure the holder to the handle.

50 In the form of construction shown in Figs. 1 to 3, the holder 4 consists of two pieces of

sheet metal 7 and 8, the metal 7 being folded into channel shape and having one flange of greater width than its other and curved outwardly at 9 to prevent cutting the wire 60 gauze 1. The part 8 of the holder is in the form of a plate received in the fold of the gauze body 1 and the front edge of said plate is curved outwardly at 10 to prevent cutting of the wire, said edge 10 being preferably 65 disposed in rear of the edge 9.

It will be observed that the two flanges of the part 7 of holder 4 are held tightly against the wire gauze by the bent ends 5 of the handle 6, that the part 8 is located in the fold 70 of the gauze body 1, and that the aforesaid handle ends retain said plate in proper place to prevent the wire gauze from pulling out of the holder. Furthermore, by folding the rear end of the gauze body as above described, two thicknesses of the wire gauze 75 are engaged by the part 8 and thus there is little danger of cutting the wire.

In Figs. 4 and 5, the holder 4 is constructed of a single piece of sheet metal bent upon 80 itself at 11 to form two parallel sides 12 and 13 whose end portions are folded inwardly and rearwardly between the body portions of said sides as seen at 14 and 15 respectively. The folds 16 curve outwardly a 85 sufficient extent to prevent cutting of the gauze body 1 and the rearwardly directed end 15 is received in the fold 3 to perform the same work as the part 8 above described.

Both forms of the invention are extremely 90 simple and inexpensive, yet they will be highly efficient and durable, the life of the improved fly sweater being at least four times that of the best of the articles now 95 manufactured. Since probably the best results are obtainable from the details disclosed, they may well be followed, but within the scope of the invention as claimed, numerous minor changes may well be made. I 100 prefer however to always round the end of the gauze body 1 to prevent the binding from pulling off.

I claim:

1. A fly swatter comprising a gauze body, 105 a channel shaped, sheet metal holder straddling the rear end of said body and secured thereto, the forward edges of said holder being curved outwardly to prevent cutting of the gauze when the latter moves from its 110 medial position, and a handle carrying said channel shaped holder.

2. A structure as specified in claim 1, one side of said channel shaped holder being of greater width than the other side thereof.

3. A fly swatter comprising a wire gauze body, the rear corners of said body being folded inwardly, and the rear end and folded corners of said body being folded forwardly, a handle, and a channel shaped sheet metal holder carried by said handle and straddling the folded rear end of said gauze body, said holder having a portion received in the fold of said gauze body.

4. A fly swatter comprising a handle, a channel shaped sheet metal holder carried by said handle, a wire gauze body having its 15 rear end folded upon itself and positioned in said holder, the sides of said holder being curved to prevent cutting the gauze, and one side being turned inwardly and rearwardly into the fold of the gauze.

In testimony whereof I have hereunto set my hand.

BENJAMIN F. KELSO.
